(57) **CLAIM**

The ornamental design for a chromatographic fluid handling device, as shown and described.

DESCRIPTION

FIG. 1 is a perspective view of the device showing our new design.

FIG. 2 is a front view of the device of FIG. 1.

FIG. 3 is a rear view of the device of FIG. 1.

FIG. 4 is a left side view of the device of FIG. 1.

FIG. 5 is a right side view of the device of FIG. 1.

FIG. 6 is a top view of the device of FIG. 1; and,

FIG. 7 is an underside view of the device of FIG. 1.

The design is for a fluid handling device for use in chromatographic separation of elements in a fluid, and comprises a generally cuboid shape with fluid handling elements mounted thereon.
